**COMBINED COVER AND HOODED MOUNTING
PLATE ASSEMBLY FOR AN ELECTRICAL JUNC-
TION BOX**

Paul J. Zerwes, deceased, late of Chicago, Ill., by Helen
E. Zerwes, Chicago, Ill., assignor to Bell Electric Com-
pany, Chicago, Ill.

Filed June 2, 1972, Ser. No. 262,926

Term of patent 14 years

Int. Cl. D13—03
U.S. Cl. D8—179

FIG. 1

FIG. 2

FIG. 3

FIG. 4

FIG. 5

FIG. 6

FIG. 7

FIG. 8

FIG. 9

FIG. 1 is a perspective view of a combined cover and hooded mounting plate assembly for an electrical junction box showing the new design with the cover member thereof in its closed position;

FIG. 2 is another perspective view of a combined cover and hooded mounting plate assembly of FIG. 1, but with the cover member in its open position;

FIG. 3 is a front elevation of the combined cover and hooded mounting plate assembly with the cover member in its closed position;

FIG. 4 is a rear elevation thereof;

FIG. 5 is a bottom elevation thereof;

FIG. 6 is a top elevation thereof;

FIG. 7 is a right side elevation thereof;

FIG. 8 is a perspective view of another form of the new design with the cover member in its open position; and

FIG. 9 is a perspective view of still another form of the new design with the cover member in its open position.

What is claimed is:

The ornamental design for a combined cover and hooded mounting plate assembly for an electrical junction box, substantially as shown and described.
